Des. 850

S. W. Gibbs, of Albany, N. Y.

Assign to

Wood, Roberts & Co., of Utica, N. Y.

Letters Patent No. 850. Dated Nov. 25th 1856.

The schedule referred to in these Letters Patent and making part of the same

To all whom it may concern:

Be it known that, S. W. Gibbs, of the city of Albany in the State of New York, have invented, or produced, a new and original design for the external configuration and ornament of a Kitchen Stove. And I do hereby declare that the following is a full and exact description of the same:

The annexed drawing, which is made a part of this specification, exhibits a perspective elevation of the stove, and discloses at a view the character of the ornaments constituting the design. The ornamental figures composing the design are in alto-relievo, and mainly correspond in character, being composed of members radiating in straight lines from the margin of a small central ornament, with intermediate concave recesses and terminating at an irregular line at their outer extremity.

These being surrounded by a smooth border corresponding in its line, to the shape of the figure enclosed.

Two of these figures, with appropriate filling up of the vacant corners are seen on the front of the oven A: and one on the end B.

The other end and side, not shown in the drawing are similarly ornamented. Like ornaments are also produced at each end of the fire box, as shown at the end C, and on each of the front doors as shown at D. The other ornaments, as upon the legs F, and the sides of the stove, are pretty clearly shown in the drawing, and to which I particularly refer.

I claim the design here described, for the external ornament and configuration of a Kitchen Stove.

Witnesses.
